UNITED STATES PATENT OFFICE.

THOMAS E. KIRKPATRICK, OF ELKHART, INDIANA, AND GEORGE E. BECK, OF CLEVELAND, OHIO.

CONDUIT-SUPPORT.

1,332,503.

Specification of Letters Patent.

Patented Mar. 2, 1920.

Application filed November 13, 1917. Serial No. 201,824.

To all whom it may concern:

Be it known that we, THOMAS E. KIRKPATRICK and GEORGE E. BECK, citizens of the United States, residing at Elkhart, Elkhart county, State of Indiana, and Cleveland, in the county of Cuyahoga and State of Ohio, respectively, have invented certain new and useful Improvements in Conduit-Supports, of which the following is a specification.

10 This invention relates to columns, and more especially to the caps thereof; and its object is to improve the supports for conduits such as are employed in housing the wires of block signal systems, interlocking systems, electric conductor wires, etc., employed in connection with railways. Ordinarily such wires are housed within a conduit or trunking substantially rectangular in form and built up of relatively narrow 15 boards and such conduits are spaced various distances above the ground surface due to the unevenness of the surface at the sides of the tracks. In order to support the conduits in level position wooden posts are ordinarily 20 employed but these soon rot or become broken or otherwise moved out of place, thereby interfering with free running of the wires in a block signal system or interlocking system, or injuring the insulation upon 25 electric conductor wires housed within the conduits.

The present invention, therefore, aims to provide a more substantial and durable support for conduits of this nature and one 30 which will securely and firmly hold the conduit in a straight line and against sagging or displacement in other directions.

Briefly stated, the device embodying the present invention includes a post and a cap 35 designed to be assembled therewith, the same having means whereby two or more of the supporting caps may be connected in parallel relation so that where two or more of the conduits are to be run side by side 40 they may be properly arranged so as to extend parallel throughout their length.

In the accompanying drawings:

Figure 1 is a perspective view of the upper end of one of the devices in condition for 45 use.

Fig. 2 is a vertical sectional view through one of the posts before assemblage therewith of its cap forming the supporting member for the conduit.

Fig. 3 is a section showing the cap assembled with the post and anchored thereto. 55

Fig. 4 is a similar section at right angles to Fig. 3, illustrating a modified form of anchoring means.

Fig. 5 is a top plan view of the structure 60 shown in Fig. 4.

Fig. 6 is a view similar to Fig. 2, illustrating a further modification of the anchoring means.

In the drawings the numeral 1 indicates 65 the post heretofore mentioned, which post is preferably formed of cement or other suitable material and in order to reinforce the post the same is provided upon its opposite sides with vertically extending ribs 2 molded integrally therewith and terminating at their upper and lower ends short of the corresponding ends of the post. While it is preferable that the post aside from the ribs 2, be rectangular in horizontal section, it 70 may be of some other form if desired, as long, however, as its upper extremity is rectangular or polygonal in order to provide against turning thereon of the conduit supporting member or cap, as will be presently 75 explained. To further reinforce the post 1 and to provide anchoring means for the cap, there is embedded in the post, in that form of the invention shown in Figs. 1, 2 and 3, a rod 3, the said rod extending vertically at 80 the center of the post except at its lower portion where it is bent laterally along a curved line in the general direction of the lower end of the post, as indicated by the numeral 4, so as to provide against being pulled loose 85 from the post. In order to provide for anchoring of the cap, the upper end of the rod 3 projects a suitable distance above the upper end of the post, as indicated by the numeral 5. 90

Various forms of caps or capitals serving as conduit supports may be mounted upon the post above described, and the present drawings illustrate a cap adapted for use in connection with a straight length of conduit. The said cap comprises a base 6 provided with forward and rearward flanges 7 which project below the plane of the under side of the base and with flanges 8 which project downwardly from the opposite sides 105 of the base. Thus the under side of the base is provided in effect with a rectangular or polygonal recess to receive and embrace

the upper end of the post 1 when the base of the cap or support is disposed upon the said end of the post. It will be understood, of course, that the flanges 7 rest against or engage the front and rear faces of the post at the upper end of the said post and that the flanges 8 rest against or engage the side faces of the post. Cast integrally with the base 6 at the opposite sides thereof are upper standing cheek pieces 9 the inner faces of which occupy planes perpendicular to the plane of the upper side of the base so that a conduit of the ordinary form, that is to say rectangular in cross section, when disposed within the channel formed by the cheek pieces and base, will be securely held against downward and lateral displacement in either direction. As clearly shown in Fig. 3 of the drawings, the base 6 is formed at its mid-portion with an opening 10 through which the upper end 5 of the rod 3 projects when the cap is disposed upon the upper end of the post, and after the same has been thus mounted on the post, the upper end of the said rod will be upset in order to rivet the end within the opening 10, as clearly shown in Fig. 3, and indicated by the numeral 11. In this manner the conduit supporting members or caps may be selectively assembled with various lengths of posts and firmly and securely anchored thereto, merely by the use of a sledge hammer.

Instead of employing the rod 3, a pipe 12 may be similarly embedded in the post 1 and may have its upper end expanded or burred down, as indicated by the numeral 13, so as to anchor the conduit supporting member in substantially the same manner as it is anchored by the riveted end 11 of the said rod. Or, if desired, the upper end of the rod 3 may be threaded, as indicated by the numeral 14, and a relatively thin nut 15 may be fitted thereto and may be turned down upon the said end so as to bear firmly against the upper face of the base 6.

Two of the supporting members may be connected or secured together, so as to be held firmly in such relative position as to support their respective conduits in parallel

relation to each other, by providing upon the outer face of one of the cheek members 9 a projecting anchoring web 16 which occupies a vertical plane and which is perforated with a bolt opening 17, it being understood that when the two conduit supporting members are properly assembled the web upon one will overlap the web upon the other with the perforations 17 in registration, whereupon a bolt may be secured through said perforations. Where more than two of the conduit supporting members are to be connected together in parallelism, both the cheek pieces 9 are formed with anchoring webs 16, as shown in Fig. 5 of the drawings, the webs having their respectively opposite faces standing in a plane across the mid-length of the channel between said cheek pieces, or in other words the mid-length of the cap member as a whole. As the members shown in Fig. 4 are cast right and left hand and their webs 16 are displaced or offset as stated, right and left hand ones of the members shown in Fig. 4 may be assembled and connected with the opposite sides of the member shown in Fig. 5, or several of the members shown in Fig. 5 may be employed in conjunction with the members shown in Fig. 4, in a similar manner.

Having thus described the invention, what is claimed as new is:

In a support, the combination with a post, and an anchor; of a cap fitted over the post and connected with the anchor, upstanding spaced cheek plates on the cap producing a through-channel, and upright webs projecting outward from and at substantially right angles to the plates and having their respectively opposite faces standing in a plane across the plates at substantially the mid-length of said channel, the webs having perforations to register with those in webs of companion and laterally aligned caps, for the purpose described.

In testimony whereof we affix our signatures.

THOMAS E. KIRKPATRICK. [L. S.]
GEORGE E. BECK. [L. S.]
